UNITED STATES PATENT OFFICE.

JOHN MCTAMMANY, JR., OF CAMBRIDGE, MASSACHUSETTS, ASSIGNOR TO
ALEXANDER MCTAMMANY, OF AKRON, OHIO.

MECHANICAL MUSICAL INSTRUMENT.

SPECIFICATION forming part of Letters Patent No. 244,069, dated July 12, 1881.

Application filed March 23, 1880. (No model.)

To all whom it may concern:

Be it known that I, JOHN MCTAMMANY, Jr., of Cambridge, in the county of Middlesex and State of Massachusetts, have invented certain 5 Improvements in Mechanical Musical Instruments, of which the following is a specification.

This invention relates to self-playing musical instruments; and it consists in the construction and combination of parts hereinafter set forth.

The drawings accompanying this specification represent, in Figure 1, a plan of the reed-cells, in Fig. 2 a side elevation, and Fig. 3 a longitudinal section, of a musical instrument 15 embodying my improvements; Fig. 4, plan of guide-frame and feed-rolls.

In the drawings above mentioned, A represents the case of my present instrument as a 20 square box open at bottom and covered by a flat top, B, the greater part of the interior of the box being occupied by the pressure-bellows, which are supported by the top of the box, the main bellows or air-reservoir being shown at 25 C as hinged at front to the front part of the top, and the pair of auxiliary bellows or feeders at D D as arranged below the first, and hinged at their rear ends to the rear end of such main bellows.

30 The reed-board and reeds occupy the front upper portion of the interior of the box A, and are screwed to the top B of the latter, the reed-board being shown at E, its reed cells or tubes at a a, &c., and its reeds at b b. The arrangement of the reed-cells and reeds is peculiar—that is to say, in lieu of securing the reeds to a board or wall which constitutes one side or boundary of the reed-cells and permits the reed to be inserted in only one position, I 35 place the reeds midway of the cells and support them in grooves c c, &c., formed in opposite sides of such cells. By this means the tongue of the reed has free play in either direction, and the reed may be inserted with its 40 tongue to the front or rear, as ample room is provided for passage of the pin or screw x², which confines the tongue to the reed and in whichever position the reed may be inserted.

To permit the reeds to be reversed in position, as stated, or to permit access to be read-

ily had to them for other purposes, I create in the upper edge of the reed-board a double rabbit, d e, the upper one, d, being small and including the upper edges of the reeds and perhaps a small portion in front of the latter, and the lower part, e, being larger and surrounding the portions of the mouths of the reed-cells in rear of the reeds, together with a portion of the reed-board sufficient to permit of insertion of screws by which the covering-plate is secured to such reed-board. This covering-plate is shown at f as adapted to fill the rabbit d e and be flush with the top of the reed-board, its function being to retain the reeds in place and cover the rear parts of the 65 mouths of the reed-cells, the front parts of such mouths being open, except when covered by the intact portion of the valve-sheet, which sheet is shown at g in the drawings. The sheet g is fed along as it fills its office of covering 70 and uncovering the reed-cells by feed-rollers, one or both of which may have an elastic periphery, the lower one of such rollers being shown in the drawings at h as affixed to or making part of a horizontal shaft, i, disposed 75 in rear of the plate f and parallel with the range of reeds, and mounted in uprights k k, erected upon the ends of the reed-board, these uprights being composed of rawhide, in order to prevent breakage and reduce friction between 80 themselves and the shaft, and to prevent rattle and noise, to which many other bearings are liable. Each end of the shaft i is fastened into a crank, l, to which one end of a pitman, m, is pivoted, the opposite ends of these 85 pitmen being pivoted to the free ends of the lower boards, n n, of the auxiliary bellows, and these pitmen are composed of rawhide, to perform the functions and secure the advantages attending the rawhide uprights k. 90

The upper feed-roll, or, more properly speaking, the presser-roll, which holds the valve-sheet in contact with the feed-roll h, is shown at o as journaled at one or both ends in a vertical slide or box, p, which plays in a channel, 95 q, in the inner edge of one of two parallel bars or rails, r r, which constitute the sides of an open frame, F, which is disposed upon the top of the case A, the end bars of such frame being shown at s s' respectively, the frame being 100

hinged at or to the top of the case in any suitable manner, but in the present instance being supported upon a rod or wire, *t*, which passes through it and into posts *u u* erected 5 upon the rear post of the said case-top.

To provide a spring-pressure for the roll *o*, in order to insure a uniform pressure of such roll upon the feed-roll or upon the music-sheet when the latter is introduced between them, I 10 place over each sliding bearing *p* a plate-spring, *v*, such spring being secured at one or both ends to the top of the frame *F* and exerting its stress upon the roll below.

In lieu of mounting the journals of the roll 15 *o* in slides in a hinged frame, or otherwise in a hinged frame, I have in some instances mounted them each directly in the ends of an elastic arm or spring, the base of which is secured permanently to the top of the instrument; or the journals of the roll may be supported in bearings in upright slotted standards erected upon the top of the case with a spiral spring placed over such boxes, and depressing them toward the lower roll. 20

25 G in the drawings represents one or more rib projections erected above the surface of the top or cover *B* of the instrument-case, and arranged between the side rails of the frame *F*, and at right angles to the latter, the purpose 30 of the rib or ribs being to raise the music-sheet above the joint between the frame and top at one or more points, and thereby prevent danger of the music-sheet being caught in such joint or between the frame and top 35 when such frame is lowered, as well as to greatly facilitate the introduction of the end of the music-sheet.

To enable the music-sheet *g* to perform the office of a valve to the reed-openings, I employ 40 a yielding presser-bar, (shown at *H* in the drawings,) adapted to rest over the entire range of such reed-openings, this bar being mounted in the front end of the frame *F*, and depressed toward the reed-board, when the 45 frame is locked to the top of the case, by springs *w w*, introduced between the presser-bar and frame, the entire separation of the two being prevented by screws, the heads of which overlap the lower edge of said presser-bar.

50 To permit of free escape of air from any one or number of the reed-cells on the arrival opposite them of the apertures in the music-sheet, I create in the presser-bar a range of holes, *x x*, &c., corresponding to the open portions of the mouths of such cells—that is, the portion not closed by the covering-plate *f*. When one or more of the holes of the presser-bar and of the traveling music-sheet unite to 55 open one or more of the reed-openings the reed 60 of such opening by outward passage of air from the pressure-bellows is sounded and a musical note produced. At other times the

solid portion of the valve-sheet interposes itself between the presser-bar and top of the reed-board to close the cells and prevent such 65 passage of air through them.

It will thus be seen that the presser-bar enables me to use a bellows, operating the reeds by a current of air outward, thereby avoiding the objections to suction-bellows before stated. 70

A crank is to be added to one end of the shaft of the feed-roll *i* outside of the adjacent pitman, by which the bellows and music-sheet are put in motion.

In lieu of hinging the frame *F* to the top of 75 the case, at one end, as stated, it may be hinged at its side, but I prefer the former.

To confine the front end or one side of the frame *F*, as the case may be, securely to the top of the case, and with pressure upon the 80 valve-sheet, I affix to the adjacent part of the instrument two or more springs, latches, or catches, *y y*, the upper or free ends of which are perforated, and operate with pins *a a* projecting from the frame in such manner that as 85 the frame is lowered to place the catches snap over and engage the pin. This form of catch may be raised by employing a spring-bolt placed upon the top of the frame and operating with a clasp secured to the instrument- 90 case with good results.

The frame *F* may be adapted to lift entirely out of the instrument, in lieu of being hinged to it; but the latter method is the most desirable.

This application shows the subject-matter of several claims which are included in a prior application now pending before the United States Patent Office, the presence of said subject-matter being indispensable to a correct 100 understanding of the improvements which are claimed in this case. Accordingly, nothing herein shown or described, but not claimed, is to be regarded as in any sense abandoned or dedicated to the public. 105

Having thus described my invention, what I claim as new, and desire to secure by Letters Patent, is—

1. The covering-plate *f*, adapted to confine the reeds in place, and covering a portion of the reed-cells outside of or in front of the reed. 110
2. In a mechanical musical instrument, the rib or erection *G*, in combination with the frame *F* and the top of the case.
3. The rawhide supports or bearings *k* for 115 the shaft of a musical instrument.
4. The combination, with the frame *F*, of the pressure-roll *o*, slides *p p*, and springs *v v*.
5. In a musical instrument, the pitmen *m*, composed of rawhide.

J. McTAMMANY, JR.
